UNITED STATES PATENT OFFICE

2,392,566

CLOTHESLINE

Abraham Arotzky, Newark, N. J.

Application July 6, 1944, Serial No. 543,653

5 Claims. (Cl. 211—119.09)

This invention relates to new and useful improvements in a pulley mechanism for supporting a line.

More specifically, the invention proposes the construction of a pulley mechanism for supporting a line such as a drying line, for instance a line for drying clothes, characterized by having a slidable support for one end of a continuous clothesline whereby the support may be disposed outside of a window when the clothes are drying and may be slid through the window inside a room for putting clothes on or taking clothes off the clothesline.

Still further it is proposed to provide a mechanism as aforesaid having a ratchet lever for moving the clothesline.

Still further it is proposed to provide a mechanism as aforesaid having a crank for rapidly moving the clothesline.

For further comprehension of the invention, and of the object and advantages thereof, reference will be had to the following description and accompanying drawing, and to the appended claims in which the various novel features of the invention are more particularly set forth.

In the accompanying drawing forming a material part of this disclosure—

Fig. 1 is a side elevation of a drying line mechanism constructed in accordance with this invention, a clothes pole, clothesline and portion of a window frame also being shown.

Fig. 2 is a plan view of the mechanism of Fig. 1.

Fig. 3 is an enlarged section on the line 3—3 of Fig. 2.

Fig. 4 is a foreshortened plan view of the window frame bracket of the mechanism.

The drying line mechanism of the present invention is for employment on a door or in a window so that the entire drying line can be disposed exteriorly of the door or window, or so that a portion of it may be pulled inside the door or window so that articles can be hung on the line, the line being maintained in operative position on the pulleys in both positions.

The line may be a clothesline and the mechanism may be attached to the outside of a window frame. When the window is open, a part of the mechanism may be pulled into the room and the clothes hung on the line in the room and successively moved outside of the room and more clothes hung on the line until the line is full or until all the clothes desired are hung on the line, whereby the part may be slid out of the room.

When so used as a clothes line, the mechanism has the advantage that a woman can hang

clothes on the line without leaning out of the window, thereby eliminating the danger of falling. This is especially advantageous when the line is fastened to the window frame of a second floor dwelling.

A further advantage of a clothes line so employed on the mechanism of the present invention is that it eliminates the need of a woman leaning out of a window into the cold air of winter or into the hot air of summer. Moreover, it enables a woman to sit in a chair while hanging up her wash, thereby facilitating the job and making it much easier for her.

The drying line mechanism may also be employed for other purposes. It may be used on the door of a drying room so that a person can hang articles to be dried without going into the drying room. The same is true of a freezing room or of a chemical tank. In short, the mechanism is adapted to be used wherever it is desired to hang articles on a continuous line in the out of doors, or in a room, tank or the like without putting any part of the person's body in such place.

25 The drying line mechanism, according to this invention, comprises a right angle bracket 10 adapted to be secured to a frame 11 by any suitable means such as screws. The frame may be the outside finishing board of a conventional house window, or it may be a door, hatch or other similar structure. The bracket has a vertical leg 12 adjacent the frame and a horizontal leg 13 having an orifice 14 in its outer end surrounded on the top face of the leg 13 with a circular row of serrations 15.

30 A support 16 having a horizontal leg 17 is adjustably secured to the leg 13, leg 17 having an orifice 18 surrounded on the bottom face of the leg 17 by a circular row of serrations 19 mating with the serrations 15. Support 16 also has a vertical leg 20 provided with four orifices 21.

35 A shouldered bolt 22 having a threaded portion at each end is secured in each orifice 21 by a lock washer 23 and a nut 24. A vertical plate 25 is secured on the outer ends of the bolts 22, plate 25 having orifices 26 in line with orifices 21 for receiving the bolts. Plate 25 is secured to the bolts by lock washers 23' and nuts 24'.

40 The portions of each bolt 22 extending through leg 20 and plate 25 are reduced, providing shoulders 27 abutting the inner faces of the leg 20 and plate 25 and providing a journal 28 between the leg 20 and plate 25. A roller 29 is rotatably mounted on each journal 28, each of the four rollers having flanges 30 at its opposite ends.

Plate 25 is provided with an upwardly extending portion 31 to which is secured a shouldered bolt 32 on which is mounted an idler pulley 33, spaced from portion 31 by a spacer 34.

A long rectangular bar 35 is supported on the bottom pair of rollers 29 and is maintained in horizontal alignment by the top pair of rollers 29 and in lateral alignment by the flanges 30, all as is clearly shown in Fig. 3. At its forward end, that is to say, the end that is remote from the frame 11, the bar is provided with an orifice 36 in which is disposed a shouldered bolt 37 on which is mounted an idler pulley 38 spaced from the bar by a spacer 39 so that it is in line with pulley 33.

A handle 40 is secured to the rear end of the bar 35. Just forwardly of the handle the bar is provided with an orifice 41 and spaced a short distance forwardly thereof the bar is provided with another orifice 42. A shouldered bolt 43 is secured in orifice 42. A main pulley 44 is rotatably mounted on bolt 43, pulley 44 being provided with a crank handle 45 and being spaced from bar 35 so that it is in line with pulleys 33 and 38 by a toothed spacer 46 forming a ratchet gear. A lever 47 is pivotally mounted at its lower end on a shouldered bolt 48 secured in orifice 41, and a ratchet 49 is pivoted to lever 47 above said bolt, the tooth 50 of the ratchet coacting with the teeth of spacer 46. Pulley 44, instead of being rotated by handle 45, may be rotated by short successive movements by successively moving lever 47 back and forth, each rearward movement of lever 47 moving pulley 44 a distance equal to one tooth of spacer 46. When lever 47 is moved forwardly the tooth 50 merely slides over the teeth of the spacer, the weight of the line and clothes thereon on the pulley 44 preventing the pulley and therefore the spacer 46 from being rotated by forward movements of lever 47.

The operation of the device is as follows:

Assuming the device is to be employed with a clothes line 51 extending over a pulley 52 secured to a clothes pole 53, the clothes line extends from the top of pulley 52 over the top of pulley 33, therefrom over the top of pulley 38 and therefrom over the top of pulley 44 and then back to pulley 52. Thus the clothes line is a continuous line having no beginning and no end. Bracket 10 is secured to the window frame and support 16 is adjusted at a suitable angle relative to leg 13 to line up the pulleys 33, 38 and 44 with pulley 53. This adjustment of support 16 is made by means of bolt 18, the serrations of legs 13 and 17 holding the support 16 in any adjusted position when bolt 18 has been tightened up.

When a woman desires to hang clothes on the line, she opens the window, takes hold of the handle 40 and pulls this back as far as it will go, thereby bringing the bar 35 into the room and also the portion of the clothes line running from the bottom of pulley 44 to the end of the bar. It is on this portion of the line that she hangs the clothes. After this portion is full, she takes hold of the crank handle 45 and turns it until the clothes move out of the window whereupon she hangs more on the line. This operation continues until the line is full or all her clothes have been hung, whereupon she pushes the bar 35 (by means of the handle 40) out of the window again and closes the window.

The lever 47 provides means for moving the clothes line a little at a time, such as when hanging up socks, neckties or other small articles. It is especially adapted for use when the mechanism

is used for other purposes than for a clothes line, for instance, if it were employed for drying photographic films in a darkroom.

The mechanism may be made of any suitable metal, plastic or other material.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A pulley mechanism comprising a support having a vertical plate, a vertical plate spaced from said support plate and secured thereto by four shouldered bolts, a pulley secured to one of said plates, a flanged roller journalled on each of said bolts between said plates, a bar rollably supported on two of said rollers and held against tilting by the other two of said rollers, said other two rollers being disposed above said bar, a pulley on one end of said bar, a handle on the other end of said bar and a pulley on said bar adjacent said handle.

2. A pulley mechanism comprising a bracket having a vertical plate, a vertical plate spaced from said bracket plate and secured thereto by four shouldered bolts, a pulley secured to one of said plates, a flanged roller journalled on each of said bolts between said plates, a bar rollably supported on two of said rollers and held against tilting by the other two of said rollers, said other two rollers being disposed above said bar, a pulley on one end of said bar, a handle on the other end of said bar, a pulley on said bar adjacent said handle, and a crank on said last mentioned pulley for rotating same.

3. A pulley mechanism comprising a bracket having a vertical plate, a vertical plate spaced from said bracket plate and secured thereto by four shouldered bolts, a pulley secured to one of said plates, a flanged roller journalled on each of said bolts between said plates, a bar rollably supported on two of said rollers and held against tilting by the other two of said rollers, said other two rollers being disposed above said bar, a pulley on one end of said bar, a handle on the other end of said bar, a pulley on said bar adjacent said handle, and a crank on said last mentioned pulley for rotating same, a ratchet gear secured to said last mentioned pulley, a lever pivoted to said bar, and a ratchet pivoted on said lever above its pivotal connection to said bar, said ratchet having a tooth coacting with said gear for rotating same in one direction only.

4. A pulley mechanism comprising a bracket having a horizontal leg, a vertical support plate having a horizontal leg secured to said bracket leg and a vertical plate spaced from said support plate and secured thereto by four shouldered bolts, a pulley secured to one of said plates, a flanged roller journalled on each of said bolts between said plates, a bar rollably supported on two of said rollers and held against tilting by the other two of said rollers, said other two rollers being disposed above said bar, a pulley on one end of said bar, a handle on the other end of said bar, a pulley on said bar adjacent said handle, a crank on said last mentioned pulley for rotating same, a ratchet gear secured to said last mentioned pulley, a lever pivoted to said bar, and a ratchet pivoted on said lever above its pivotal

connection to said bar, said ratchet having a tooth coacting with said gear for rotating same in one direction only.

5. A pulley mechanism comprising a bracket having a horizontal leg, a support having a horizontal leg, said legs having overlapping orificed portions, a bolt in said orifices securing said portions together, the adjacent faces of said portions being serrated around said orifices, said support further having a vertical leg, and a vertical plate spaced from said vertical leg and secured thereto by four shouldered bolts, a pulley secured to one of said plates, a flanged roller journaled on each of said bolts between said leg and plate,

10 a bar rollably supported on two of said rollers and held against tilting by the other two of said rollers, said other two rollers being disposed above said bar, a pulley on one end of said bar, a handle on the other end of said bar, a pulley on said bar adjacent said handle, a crank on said last mentioned pulley for rotating same, a ratchet gear secured to said last mentioned pulley, a lever pivoted to said bar, and a ratchet pivoted on said lever above its pivotal connection to said bar, said ratchet having a tooth coacting with said gear for rotating same in one direction only.

ABRAHAM AROTZKY.
